DIE BUTTON

Hans W. Wiersheim, Norwalk, Ohio, assignor to Kuhlman Machine Company, Norwalk, Ohio, a corporation of Ohio

Filed Apr. 2, 1964, Ser. No. 356,862
6 Claims. (Cl. 83—630)

This invention relates to an improved die button construction which may be used in a punch or blanking press in which removable die buttons are utilized. More specifically, this invention relates to an improved die button which may be used in existent die sections or die button retainers and which will prevent damage to the die button retainer when the improved die button becomes packed with slugs of the metal being punched or when the die button is broken due to misalignment of the punch or other malfunction of the machine.

Punching and blanking presses throughout the industry commonly use replaceable die buttons held in a die section or die button retainer. Interchangeable die buttons are advantageous in many punching and blanking operations since a number of holes of various sizes or shapes of blanks may be formed on a single power press through use of a series of interchangeable punches and die buttons. The die buttons, which may be press fit or otherwise secured within a die section or die button retainer plate, may be easily and economically replaced when their cutting edges have become worn and are now available in many various sizes and shapes throughout the industry.

Still a further advantage in using die buttons in punch or blanking presses, in addition to their interchangeability and economy, is the fact that the die buttons themselves, being relatively inexpensive, are frequently the only portion of the die section of the press which is damaged due to malfunction in the punching or blanking operation. For instance, if the punch, during a punching operation, becomes bent or otherwise gets out of alignment with the die, the damage will be confined to the die button itself, rather than the more expensive die button retainer plates or die sections. Furthermore, when the die member becomes packed with slugs or waste material, the damage to the die portion is often confined to the immediate surfaces of the die button itself in contact with the punch. Thus, replacement of the die button only is necessary to restore the press to operation.

However, in aggravated cases of slug-packing, the punch may create stresses in the die button which are transmitted to the die section or die retainer plate holding the die button causing the adjacent areas of the die section or die retainer plate to fail. This is particularly true in operations requiring high punch forces such as those performed on relatively thick materials in which a blank or slug is most likely to be retained within the die.

It has been discovered that damage to the die section from slug-packing within a die button may be prevented by use of an improved die button constructed to absorb stresses and allow breakage of the die button without damage to the adjacent die sections.

Accordingly, it is an object of this invention to provide an improved die button for use in punch and blanking presses which, because of its construction, will not transmit breaking stresses to the adjacent surfaces of the die section or die retainer plate holding it.

It is another object of this invention to provide an improved die button construction which may be used in existing die sections or die retainer plates which has a stress absorbing means to prevent breaking stresses from being transmitted from the punch to the adjacent surfaces of the die retainer plate or die section.

It is a further object of this invention to provide an improved die button which may be press-fit or otherwise

2

secured within a conventional die button retainer or die section and which will prevent breaking stresses from being transmitted from the punch through the die button to the adjacent surfaces of the die button retainer or die section when the punch is out of alignment with the die button or when the die button becomes packed with slugs or blanks.

Other objects and advantages of this invention will be apparent from the following specification and drawings in which:

FIG. 1 is a view in perspective of an improved die button of this invention;

FIG. 2 is a plan view of the die button shown in FIG. 1;

FIG. 3 is a cross sectional view in elevation, taken along the line 3—3 of FIG. 2, showing the construction of the improved die button; and

FIG. 4 is a schematic view in cross section showing the improved die button of this invention press-fit in a die section or die retainer and showing the position of a cooperating punch axially aligned above the improved die button.

FIG. 1 shows an improved die button of this invention which generally comprises a cylindrical body 10 having an axially extending punch hole 11 throughout its length. The punch hole 11 is, of course, the size and shape as determined by the size of the blank or hole to be punched in the punching operation. The punch hole 11 is slightly larger in diameter than the diameter of the punch 12, shown in FIG. 4, which, when forced against the upper surface of the blank 13, causes the blank 13 to shear between the edge 14 of the punch and the edge 15 of the die button, forcing a slug of material through the punch hole 11 in the die button.

As seen in FIGS. 3 and 4, the lower portion of the punch hole 11 is outwardly flared to provide a radially relieved zone, generally designated by the reference numeral 16, which gives additional clearance for the slug to drop through the die button after it has been pushed past the upper part of the punch hole 11.

Dies and die buttons having radially relieved punch holes are well known in the art. However, due to the fact that the dies and die buttons must withstand considerable stress upon the cutting edges 15 in a direction parallel with the movement of the punch (see FIG. 4), it is impractical to flare or relieve the punch hole 11 in the die button throughout its length, since the cutting edge 15 must have sufficient support immediately below the upper surface 17 of the die or die button. Therefore, the punch hole 11 must have uniform cross section for a substantial length of the die button, as illustrated in FIGS. 3 and 4. Due to this necessity of maintaining the uniform cross section of the punch hole 11 throughout a substantial length of the die button, the problem of jamming or packing of slugs or blanks within the upper portion of the die or die button persists. As shown in FIG. 3, a slug 18 may become cocked or wedged within the upper portions of the punch hole 11. When this occurs, the punch 12, on its next downward stroke will

strike the slug 18 and, depending upon the size of the slug 18 and the manner in which it is jammed in the narrow portion of the punch hole 11, will either push the slug 18 out of the die button or further impact it, leaving a second slug on top of it. If a number of impacted slugs 18 build up within the die button, or if the metal being worked is relatively heavy, a subsequent stroke of the punch 12 will transmit sufficient force through the slug 18 to crack the die button, distort it or bend the punch 12. Once the die button has become distorted or misaligned with the punch 12, subsequent strokes of the punch 12 will result in its cutting edges 14 striking

the punch 12. It is to be understood that the improved die button of this invention may be used in any type of die section or die retainer plate which has a stress absorbing means to prevent breaking stresses from being transmitted from the punch to the adjacent surfaces of the die retainer plate or die section.

the upper surface 17 of the die button and will injure the punch 12 as well as the die button.

As shown in FIG. 4, the die buttons, which are press-fit or securely held within the die section or die retainer 19 and backing plate 20, will transmit the pressures from the punch 12 and, in many case, cause injury to the die section or die retainer 19. When working with materials requiring relatively large punching force, the die button will transmit sufficient force from the punch 12 through the jammed slug 18 to crack adjacent areas of the die section 19. If the die section 19 has an upwardly extending boss 21, as shown in FIG. 4, this boss 21 is likely to be fractured along with the upper areas of the die button. As previously explained, the die sections 19 are relatively expensive in comparison with the smaller die buttons and require more time to replace, when fractured as described above.

Accordingly, in the improved die button of this invention, a resilient annular band 22 is circumjacent the upper portion of the cylindrical body 10 of the die button as shown in FIGS. 3 and 4. The body 10 of the die button has an upper portion 23 of reduced diameter and a land 24 which supports the resilient band 22 as best shown in FIGS. 1, 3, and 4. The resilient band 22, which may be made of any resilient material such as hard rubber, Teflon, or other resilient synthetic resinous materials, is press-fit or adhesively secured around the upper portion 23 of the die button.

The purpose of the resilient band 22 around the upper portion 23 of the die button is to absorb the force transmitted from the punch 12 through the slug 18 to the wall of the upper portion 23 of the die button and prevent this force from cracking the boss 21 or adjacent area of the die retainer 19. As illustrated in FIG. 3, a slug 18, which becomes cocked within the punch hole 11, upon the next stroke of the punch 12, will transmit lateral force to the wall of the upper portion 23 of the die button, and, particularly if the slug 18 is of a relatively heavy material, will dig in at its edge 25 and crack the wall of the upper portion 23 of the die button in the area indicated by reference number 26. As soon as the wall of the upper portion 23 of the die button is fractured, the lateral force exerted by the impacted slug 18 will cause the broken section of the die button to slightly compress the resilient band 22. As the resilient band 22 is compressed, the slight radially outward movement of the broken section of the die button will increase the diameter of the punch hole 11 in that area, freeing the impacted slug 18 which is then pushed through the die button by the punch 12. Thus, only a slight amount of compression is required of the resilient band 22 to release the impacted slug 18 and permit the punch 12 to complete its downward movement. Although the die button itself has become damaged and must be replaced, the action of the resilient band 22 has prevented further damage to the boss 21 of the more expensive die section 19. The punch press may be quickly repaired by a placement of the die button only and operation may be resumed. Furthermore, since the slight amount of compression by the resilient band 22 has released the impacted slug 18, subsequent cycles of the punch 12, prior to repair, will not allow a number of slugs 18 to be built up which may eventually cause damage to the punch 12 itself, as previously explained. Therefore, the resilient band 22 of the die button protects the die section 19 from serious damage and also prevents a buildup of impacted slugs 18 which may cause damage to the punch 12.

The resilient band 22 should be dimensioned such that its outer surface extends slightly beyond the outer surface of the cylindrical body 10 of the die button, as shown in FIG. 3. This insures a snug fit of the entire improved die button within the die retainer or die section 19 since the resilient band 22 must be slightly compressed so that its outer surfaces are flush with the outer surfaces

of the cylindrical body 10 when the die button is in place, as shown in FIG. 4. The resilient band 22 should have an axial length approximately equal to the distance from the upper surface 17 of the die button to the start 5 of the flared portion 16 of the punch hole 11 because the action of the resilient band 22 is needed throughout the upper portion of the punch hole 12 where the slugs are most likely to become impacted. It is not necessary that the resilient band 22 extend circumjacent the flared portion 16 of the punch hole 12, since this portion 10 has increased clearance and will not permit slugs 18 to become impacted in the manner shown in FIG. 3.

It is to be understood that this invention may be adapted to die buttons of irregular outer dimensions and 15 also to die buttons for punching and blanking irregular configurations and having irregular axial openings. It will be apparent that various changes and modifications will be made in the specific details discussed above and as shown in the drawings without departing from the 20 spirit of the attached claims.

What I claim is:

1. In a die button adapted to be rigidly secured in a punch die section and comprising a body portion, a punch aperture of preselected diameter axially extending throughout said body portion, said aperture being of uniform size from the upper face of said die button to a point intermediate said die button and outwardly flaring, radially increasing from said intermediate point to the lower face of said die button, the improvement comprising an upper body portion of decreased external size axially extending from said upper face to approximately said intermediate point, and an annular band of a resilient material circumjacent said upper body portion, the radially outer surface of said band extending slightly beyond the outer 30 surface of said die button.

2. An improved die button for use in a punch die section comprising a cylindrical body, an axial punch aperture of preselected size throughout said body portion, said aperture having a radially increasing, tapered portion extending from a point intermediate the upper and lower faces of said body portion to said lower face, an upper portion of said body of reduced external diameter extending axially from said upper face of said body to approximately said intermediate point, and an annular 40 resilient band circumjacent said upper portion of reduced diameter.

3. An improved die button comprising a cylindrical main body portion and an upper cylindrical body portion of decreased diameter, an axial punch aperture extending throughout said die button, said punch aperture having a uniform cross section in said upper body portion and an outwardly tapered, radially increasing cross section through said main body portion, and an annular resilient washer circumjacent said upper body portion, the radially outer surface of said resilient washer extending slightly beyond the outer surface of said main body portion.

4. An improved die button adapted to be rigidly secured within a cavity in a die section, said die button comprising a body portion with upper and lower faces 60 and having substantially the same outer dimensions as said die section cavity, a punch aperture extending through said body portion, said punch aperture being of uniform size at its upper end near said upper face and being outwardly tapered at its lower end near said lower face, a peripheral groove on the outer surface of said body portion extending axially from said upper face to a point intermediate said upper and lower faces and an annular band of resilient material within said groove and circumjacent said body portion with the radially outer surface of said band in contact with the walls of said die section cavity when said die button is rigidly secured therein.

5. The improved die button of claim 4 wherein said body portion is substantially cylindrical.

6. The improved die button of claim 4 wherein said radially outer surface of said resilient band, when said die button is not mounted in a die cavity, extends slightly beyond the outer surface of said body portion whereby said annular band will be compressed in a radially inward direction when said die button is rigidly secured in said cavity of said die section.
